UNITED STATES PATENT OFFICE.

WILLIAM T. RUTLEDGE, OF SANTA ANA, CALIFORNIA.

LINE AND CIRCUIT BREAKER.

Application filed January 26, 1921. Serial No. 440,003.

To all whom it may concern:

Be it known that I, WILLIAM T. RUTLEDGE, a citizen of the United States, residing at Santa Ana, in the county of Orange and 5 State of California, have invented new and useful Improvements in Line and Circuit Breakers, of which the following is a specification.

This invention relates to line breakers for 10 high voltage transmission lines, and particularly pertains to automatic line breakers.

An object of this invention is to provide 15 interlocking connections disposed at suitable points in a transmission line, so formed that the normal tension of the line will hold the connection intact but will disengage when the intervening section of the transmission line breaks so as to cause the ends of the broken line to detach from intact portions of 20 the line and fall to the ground.

Another object is to prevent live ends of 25 broken wires from coming in contact with the ground.

Other objects will appear hereinafter. 30 The accompanying figures illustrate various applications of this invention to electric transmission lines, in which:

Figure 1 is a view of a part of a transmission line showing an application of the 35 invention.

Figure 2 is a view in longitudinal section of an upper connecting member used in the transmission line shown in Figure 1.

Figure 3 is a view in end elevation of the 40 member shown in Figure 2.

Figure 4 is a view in section of the lower connecting member used in the transmission line shown in Figure 1.

Figure 5 is an end elevation of the member 45 shown in Figure 4.

Figure 6 is a view in front elevation of the jointed member of the transmission line shown in Figure 1.

Figure 7 is a view in end elevation of the 50 member shown in Figure 6.

Figure 8 is a view of a transmission line illustrating another application of this invention.

Figure 9 is a view in section of a modification 55 of the member shown in Figures 4 and 5; and

Figure 10 is a view in end elevation of same.

Figure 11 shows another modification of 60 the member shown in Figure 4; and

Figure 12 is a view in side elevation of same.

More specifically, 15 indicates a transmission line supporting tower and 16 denotes a cross arm from which cables 17-17 extend and connect with insulators 18-18. Transmission wires 19-19 are supported by the insulators and cables and in the application of the invention as shown in Figures 1 and 8, the usual T-L connections 20 are interposed between the wires and the insulators to the L portions of which are connected electrical conductors 21 extending below the cross arm and spaced from the tower.

The essence of this invention resides in 70 the automatically disengageable connections interposed in the line; 22 indicating one such connection which comprises two interlocking members 23 and 24 formed with sockets in one of which is a ball 25 secured 75 therein by a pin 26, thus providing a ball and socket connection. This connecting member is shown in Figure 1 as interposed between each T-L member and the insulators 18. Two other connections 27-27 are 80 secured to the lower extremities of the T-L members and comprise two similar socketed members 28-28 having a ball 25 secured to one in the same manner as that just described. Each socketed member 28 is provided with contacts 29 preferably formed of laminated sheets of copper and so formed as to tend to normally hold the members apart. Interposed midway in the conductor 21 in the construction shown in Figure 1 is 90 a hinge 30, the conductor in this case being of rigid construction and adapted to force the T-L members farther apart than the positions they would normally assume, thus placing the conductor with the connections 95 under slight pressure to hold the parts intact. This hinge 30 consists of two hinged members 31 and 32 rotatably mounted on and secured together by a pin 33. The member 31 is of single blade knife form and the member 32 is split to receive the member 31, which member is provided with the shoulders 34 upon which the ends of the split member repose. This hinge is rigidly 100 fixed to the ends of the conductor, the pin 105 being positioned below the center line of the conductor so that a thrust will hold this hinge locked in a closed position. The hinge is likewise a conductor, its purpose being to provide a conductor that is nor-

mally rigid, but which may be caused to buckle when the lines of force which normally hold it locked are changed.

Another application of this invention to transmission lines is shown in Figure 8, but in which another set of the connections 22 comprising the interlocking members 23 and 24 is used to connect a conductor 35 to the T-L members 20-20. This conductor 10 may be of any suitable construction and may be rigid or flexible but is here shown as consisting of a length of wire which is slightly shortened so that the wires 19-19 and connections 22 are placed under a tension to assure engagement of the interlocking members.

A modified construction of the connection shown in Figures 4 and 5 is illustrated by Figures 9 and 10, and comprises a socketed member 40 of circular form adapted to receive another member 41. This connection is preferably for use in connection with a rigid conductor 42. Figures 11 and 12 illustrate another modification thereof 25 which consists of a forked member 43 adapted to receive and frictionally retain a bladed member 44, which connection is also for use on rigid conductors 45.

The automatic operation of the parts described and illustrated in Figure 1 is as follows:

When a section of the wires such as 19 breaks from any accidental cause the tension upon the cable 17 and the interlocking members 23 and 24 of the connection 22 is released and the tension upon the T-L pieces is also relieved. The weight of this T-L piece and the attached portion of the broken wire causes the member 24 carrying the ball 25 to fall out of connection with the other member which is secured to the cable, the weight of these parts then comes upon the members 28 of the rigid conductor 21 causing it to disengage from the other member. Thus the T-L piece with the attached part and the broken end of the wire falls to the ground, this action also occurring at the pole or tower on the other side of the breaking point. Should the member 27 not readily disengage while in the horizontal position the weight of the parts will cause the hinge 30 to buckle and allow that end of the conductor to swing to a vertical position and the members 28 will then readily disengage. Thus the entire section of wire between the two adjoining poles disconnects and falls to the ground leaving no dangling wires on the line. The normal tension of the connected wire on the other side of the tower will hold all connected parts intact. The conductor 21 will disengage also at its other end and fall to the ground leaving no live portions of the line about the tower.

The construction shown in Figure 1 may

be employed without the use of the connection 22. In such case, when the wire breaks, the spring contacts 29 will force the members 28 apart and the conductor 21 will drop from position to the ground, thus breaking the circuit leaving the broken wire attached to the cable 17, but disconnected from the circuit so as to be harmless.

When the construction and arrangement of parts shown in Figure 8 is employed the 75 connections 22-22 secured to either end of the T-L piece adjacent the broken wire will fall to the ground when a wire breaks. The connection on the other side of the cross arm which connects the conductor to the other T-L piece will also disengage. Thus the conductor, together with the broken end of the wire and the attached T-L piece will fall to the ground detached entirely from the circuit. 80

Various arrangements of the connections shown and described may be employed in transmission lines to suit varied requirements, and whereas, I have shown specific constructions and arrangements I may use 90 various combinations of the salient features of this invention as come within the scope of the appended claims. 85

I claim:

1. In an electric transmission line, the 95 combination of a supporting tower having a cross arm, non-conducting supporting cables secured to said tower and supporting the electric wires, interlocking members disposed between said cable and the wire 100 and adapted to remain interlocked when under a tension stress, T-L pieces fixed to the wire, a conductor connecting said T-L pieces to provide a circuit which circumvents said tower, interlocking members disposed in said conductor adapted to remain normally interlocked but to disengage when any section of the wires break whereby all conductive parts of the lines between towers fall to the ground when the wire between 105 said towers breaks.

2. In an electric transmission line, a cross arm, a pair of non-conducting supports extending from opposite sides of said cross arm, a pair of hangers connected to said supports by a ball and socket joint adapted to remain interlocked when under a tension stress, electrical conductors connecting said hangers, and an interlocking member connecting said conductors normally held 110 in engagement by tensile pull imparted to said hangers and adapted to automatically disengage on relief of the pull on said hangers. 115

3. In an electric transmission line, a cross arm, a pair of non-conducting supports extending from opposite sides of said cross arm, a pair of hangers connected to said supports by a ball and socket joint adapted 120 to remain interlocked when under a ten- 125

- sion stress, an electrical conductor extending between said hangers, and an interlocking member connecting each end of said conductor to said hanger, normally held in engagement by a pull imparted on said hanger and adapted to disengage on relief of the pull whereby the length of conductor will be freed at its ends and disengaged from the hangers.
- 10 4. In an electric transmission line, a cross arm, a pair of non-conducting supports extending from opposite sides of said cross arm, a pair of hangers connected to said supports by a ball and socket joint adapted to remain interlocked when under a tension stress, a rigid electrical conductor connecting said hangers, and an interlocking member connecting the ends of said conductor to said hangers normally held in engage-
- ment by tensile pull imparted to said hangers and adapted to automatically disengage on relief of the pull on said hangers.
5. In an electric transmission line, a cross arm, a pair of non-conducting supports extending from opposite sides of said cross arm, a pair of hangers connected to said supports by a ball and socket joint adapted to remain interlocked when under a tension stress, a rigid electrical conductor extending between said hangers, and an interlocking member connecting each end of said conductor to said hanger, normally held in engagement by a pull imparted on said hanger and adapted to disengage on relief of the pull whereby the rigid conductor will be freed at its ends and disengage from the hangers.

WILLIAM T. RUTLEDGE.
